UNITED STATES PATENT OFFICE.

LOUIS L. CLAXTON, OF PATERSON, NEW JERSEY.

FOLDING BOX.

SPECIFICATION forming part of Letters Patent No. 723,830, dated March 31, 1903.

Application filed May 17, 1902. Serial No. 107,849. (No model.)

To all whom it may concern:

Be it known that I, LOUIS L. CLAXTON, a citizen of the United States, residing at Paterson, in the county of Passaic and State of New Jersey, have invented a new and useful Folding Box, of which the following is a specification.

This invention relates generally to paper boxes, and more particularly to a knockdown or folding box, the object of the invention being to provide a box of this kind which can be folded into a neat and compact form for shipment or storage and one which can be quickly and easily set up into a box form when desired and one in which the parts will interlock when set up into box form, thereby providing a thoroughly serviceable article.

Another object of the invention is to so construct the box that great economy in cutting the blank is obtained, and a still further object is to provide a construction of knockdown or folding box in which various forms of locking means may be employed, all of which are within the general scope of the invention.

With these various objects in view the invention consists in the novel features of construction and combination and arrangement, all of which will be fully described hereinafter and pointed out in the claims.

In the drawings forming part of this specification, Figure 1 is a perspective view of a knockdown box constructed in accordance with my invention, said box being folded for shipment or storage. Fig. 2 is a perspective view showing the box set up. Fig. 3 is a perspective view showing the position the parts assume when the box is half-folded. Fig. 4 is a plan view of the blank, the end laps being of the same length. Fig. 5 is a plan view of one end of a blank, the end laps being of unequal length, one end lap being adapted to extend entirely across the end of the box. Fig. 6 is a detail perspective view showing the manner of connecting the end laps by means of a gummed tape. Fig. 7 is a detail perspective view showing one end lap connected to the opposing end lap. Fig. 8 is a detail perspective view showing one end lap extending entirely across. Fig. 9 is a view similar to Fig. 8, the end being set up and held in place by means of the divided piece carried

by the sides. Fig. 10 is a detail perspective view showing the end laps connected by means of the gummed tape, the end being turned down for the purpose of more clearly illustrating the openings at the juncture of the side and end flaps.

In constructing a box in accordance with my invention I employ a blank which is cut in substantially the form indicated in Fig. 4 and is scored along the lines 1, 2, 3, and 4, the lines 1, 2, and 3 being parallel to each other and the lines 4 being parallel to each other and at right angles to the lines 1, 2, and 3, thereby subdividing the blank into the bottom A, sides B, cover C, ends D, and end lap E and also providing the cover C with flaps C'. A longitudinal score 5 is produced centrally of the bottom A, said score-mark extending also through the ends D, and at the juncture of the end and bottom is produced a transverse slit F, which slit is in alinement with the score-line 4, and the bottom is also provided with transverse slits F', parallel to the slits F, and connecting the slits F and F' is the longitudinal slit F², said slit F² being in alinement with the score-mark 5. These slits F, F', and F² facilitate the folding and unfolding of the box, as hereinafter explained. The ends and end laps are separated by means of slits G, and in practice I prefer to make this slit angular, as indicated at G', in order to provide the ends with lateral projections or extensions H, which lateral projections or extensions are adapted to engage the openings I, produced in the sides adjacent to their edges and along the score-mark 4, so that the said openings or apertures will be at the angle or corner of the box.

In Figs. 8 and 9 I have shown small pieces of pasteboard K, secured upon the inner face of the sides B, adjacent to their ends, and against which the end D is held by the end lap E, as most clearly shown. In Fig. 9 it will be noticed that the end D is made higher than the end lap and the projecting portion turned inwardly, as shown.

In Figs. 1, 2, 3, 4, and 10 the end laps E are of the same length and are connected by means of a gummed tape M.

In Fig. 7 the end laps are of substantially the same length; but their meeting ends overlap and are secured together.

In Figs. 5, 8, and 9 the end laps are of unequal length, one lap being of a length sufficient to extend entirely across the end of the box, and this longer end lap is scored at E' to facilitate the folding of the box.

In constructing the box the blank is first formed and the ends of the end laps united. The box is then ready for use. In Fig. 1 I have shown the box folded for shipment or storage, and it will be noted that it can be folded into a very small and neat package.

In Fig. 2 I have shown the box set up, and it will be observed that the laterally-projecting extensions carried by the ends enter into the openings or apertures produced in the sides, thereby interlocking the ends and sides and holding the said ends in an upright position. The cover can then be turned down and the box completed. The longitudinal and transverse slits produced in the bottom greatly facilitate the folding and unfolding operations of the box. In Figs. 8 and 9 the lateral projections and side openings are dispensed with and small pieces of pasteboard K serve to hold the ends in their upright positions.

It will thus be seen that I provide an ex-

ceedingly simple construction of folding box and one which can be quickly and easily folded or unfolded, as desired.

It will be understood that I may construct the box with or without the cover or lid, as 35 desired, and, furthermore, the means for retaining or supporting the ends in an upright position may be entirely dispensed with.

Having thus fully described my invention, what I claim as new, and desire to secure by 40 Letters Patent, is—

1. A knockdown or folding box comprising in one piece, a bottom, sides, ends and end laps, the bottom and ends being scored, and a plurality of longitudinal slits, and a plurality of transverse slits, each longitudinal slit connecting two of the transverse slits midway their ends, said slits being adapted to facilitate the folding of the box. 45

2. A knockdown or folding box comprising 50 the bottom, sides, ends and end laps, the pieces arranged upon the inner face of the sides adjacent to each end and adapted to bear against the end pieces adjacent their upper edges, the end laps holding the ends against 55 said pieces, as specified.

LOUIS L. CLAXTON.
